NECKTIE

Alfred F. Taborski, Buffalo, N. Y.

Application August 14, 1946, Serial No. 690,427

3 Claims. (Cl. 2—153)

1

This invention relates to neckties and particularly to those which are preformed and attached in that condition to the neckband or collar of a shirt.

An object of the invention is to provide an improved, simple and inexpensive construction of preformed neckties which will have the appearance of the ordinary, unpreformed tie; with which a plurality of drapes or breast pieces or other ornamental wings or members may be interchangeably connected to the knot portion in order to vary the visual effect of the complete tie; and with which the wings or drapes may be interchanged in a simple manner without special tools other than a screw driver.

Other objects and advantages will be apparent from the following description of some embodiments of the invention, and the novel features will be particularly pointed out hereinafter in connection with the appended claims.

In the accompanying drawing:

Fig. 1 is a face elevation of a tie constructed in accordance with this invention; and

Fig. 2 is a side elevation with parts broken away to show interior details of construction.

In the illustrated embodiment of the invention, the improved tie includes a knot portion 1 of any suitable construction having a recess 2 in its lower end face, which recess has a portion of reduced cross section 3 well in the interior of the knot portion. Loops 4 may be applied to opposite sides of the knot portion adjacent its upper end for attachment to a resiliently stretchable band (not shown) that encircles the neck of the wearer in order to hold the tie in position. A drape or breast piece 5 is gathered together at one end around and secured to a stiffening element or pin 6 which is insertable endwise into and out of the recess 2 at the inner end portion 3 thereof. This pin 6 extends beyond the end of the drape into the reduced portion 3 of the recess, but the end of the drape extends into the recess 2 as shown.

The pin 6 is exposed at the rear of the drape and it is provided at spaced intervals along its outer end with a plurality of transverse passages 7. A small pin 8 is insertable into and out of each of these transverse passages 7, and at its outer end is formed into an eye 9. All of these passages 7 extend in a direction from front to rear, and the pin 8 extends into any one of these passages from the rear. A long screw 10, having a head 11, has its shank passing freely through the eye 9 in a direction parallel to the longitudinal axis of pin 6, and within and along an elongated recess 12 in the body of the knot portion which is

2

parallel to but spaced rearwardly from the reduced portion 3 of the recess. An outwardly opening cavity 13 provided in the rear face of the body portion, extends inwardly to intersect and cross the passage 12. A nut 14 is disposed in this cavity 13, and the screw 10 is threaded through this nut.

By tightening the screw 10, the stiffening pin or element 6 may be forced endwise into the recess 2 and releasably confined therein as shown in Fig. 2. To remove the drape one merely turns the screw 10 in a direction to release it from the nut 14, and then the pin 6 with screw 10 attached may be removed from the knot portion, and a new drape having a different appearance substituted. The nut may be anchored against turning in the cavity 13.

The front face of the knot portion may be covered or ornamented in any desired manner, but in the example illustrated, a recess 15 is provided in the front face and is preferably of cross-shape in outline. In this recess is disposed a hollow container 16 of similar outline having an opening closed by a screw type closure 17. This container is preferably of glass or transparent plastic, and may carry a liquid or other substance. For example it may be a hollow container containing holy-water or perfume, or whatever one may desire to carry, or it may be of colored liquid which gives an ornamental appearance. This container may be removably secured in the recess in any suitable manner such as by wedging it therein, or by having rubber lined side walls which provide a frictional grip on the container, or in any other suitable manner.

It will be understood that various changes in the details, materials and arrangements of parts, which have been herein described and illustrated in order to explain the nature of the invention, may be made by those skilled in the art within the principle and scope of the invention, as expressed in the appended claims.

I claim:

1. A preformed necktie comprising a knot portion having therein a recess opening downwardly through its lower end, an anchorage element removably disposed in said recess and depending therefrom, a drape secured over and to the lower end of said element and extending into said recess, said element having in its depending end a transverse passage, a pin removably received in said passage and having a loop on its outer end, a screw having its shank threaded and passing through said loop and parallel to said element, 55 said knot portion having an elongated passage

along which said shank of said screw extends, a nut in said knot portion across said elongated passage and into which said screw is threaded, the head of said screw abutting against said loop to draw said element into said recess and hold it there.

2. A preformed necktie comprising a knot portion having therein a recess opening downwardly through its lower end, an anchorage element removably disposed in said recess and depending therefrom, a drape secured over and to the lower end of said element and extending into said recess, and a screw disposed generally parallel to said element and rotatably connected thereto, said knot portion having a nut incorporated therein, and said screw being threaded into said nut to draw said element into said recess and releasably hold it to said knot portion.

3. A preformed necktie comprising a knot portion having therein a recess opening downwardly through its lower end, an anchorage element removably disposed in said recess and depending

therefrom, a drape secured over and to the lower end of said element and extending into said recess, said element carrying a laterally extending arm having a transverse aperture, a screw passing through said aperture and extending in a direction generally parallel to said element, said knot portion having a nut portion into and out of which said screw may be threaded to secure said element in said recess.
